METHOD OF AND APPARATUS FOR
CONTROLLING FLOW

Ralph W. Pressey, Newtown Square, Pa.

Application March 17, 1939, Serial No. 262,372

8 Claims. (Cl. 237—9)

My invention is a method of and apparatus for controlling flow which is responsive to slight variations in the pressure of a fluid, and particularly of a condensable vapor such as steam, flowing through a conduit. It is primarily designed to maintain the flow at a constant pressure within very close tolerances by apparatus which is simple, inexpensive and free from parts likely to deteriorate or get out of order.

My improved flow controller is further designed to be immediately responsive to an increase in pressures and more slowly responsive to a decrease in pressure, and it includes a valve which is immediately moved toward closing position upon any rise in pressure and which is opened slowly upon a drop in pressure.

My improved flow controller is particularly applicable to the control of low pressure steam heating systems where it is desired to maintain an adjustably constant low pressure of steam on radiators notwithstanding changes in the radiating circuit or changes in the high pressure steam supply line. My improvements may, however, be applied to the control of flows of gaseous or liquid fluids at high or low pressure.

In a preferred embodiment of my invention, variations in pressure of vapor flowing in a conduit act upon condensate from such vapor to vary the relative quantities of condensate in communicating vessels. The consequent variations in liquid head in one of the vessels effect actuation of a valve controlling the vapor conduit. One of the vessels preferably comprises a pipe section depending from a T-fitting of the down-flow side of the vapor conduit and has its bottom closed or plugged so as to form a receiver or reservoir in which condensate from the vapor system collects to a depth regulated by a trapped overflow line. The other vessel preferably consists of a receptacle suspended from a valve operating arm and communicating with the reservoir through a flexible tube terminating in a nozzle projecting into the receptacle and preferably having an end port and a side port spaced from one another and of different areas.

The characteristic features and advantages of my improvements will further appear from the following description and the accompanying drawing in illustration thereof.

In the drawing, Fig. 1 is a side elevation of a flow controller embodying my improvements; Fig. 2 is an enlarged fragmentary vertical sectional view of the valve-operating receptacle; Fig. 3 is an enlarged fragmentary vertical sectional view of the air valve of the valve-operating receptacle; 50

and Fig. 4 is a side elevation of a modified form of valve-operating receptacle.

As illustrated in Figs. 1, 2 and 3 of the drawing, a high pressure conduit 1 communicates with a low pressure conduit 2 through a valve 3 having a valve stem 4 vertically reciprocable, to open and close the valve, by an arm 5 fulcrumed on the bearing 6 and guided by the guides 7; the valve stem being normally biased toward open position by a counterweight 5'.

The low pressure conduit section 2 includes a T-fitting 8 having one of its ports communicating with a distribution line 9 and the other of its ports communicating with a depending pipe section 10 having a closed bottom forming a condensate receiver or reservoir 10' in the lower portion thereof. A valved overflow tube 11 communicates with the pipe section 10 to limit the depth of condensate in the reservoir 10' and discharges to waste through a sealed or float-controlled trap 12 which, while maintaining the pressure in the system, permits the escape of excess condensate from the pipe section 10 but prevents the escape of vapor.

25 The lower portion of the reservoir 10' communicates, through the valved fitting 13 and flexible tube 14, with a nozzle 15 adjustably mounted in the bottom of the receptacle 16 which is suspended by a tension member 17 from the valve operating arm 5. The nozzle 15 has a lateral port 18 within the receptacle 16 adjacent to the bottom thereof and an end port 19 of larger area than the port 18.

A gauge glass 20 is mounted on the receptacle 16 so as to communicate therewith near the top and bottom thereof. An air escape valve 21 is mounted on top of the receptacle and has a port 22 controlled by a float valve 23 by which escape of air from the receptacle is permitted but the escape of liquid is prevented.

In the operation of the device, condensate from vapor flowing through the conduit system collects in the reservoir 10'. With the valve 3 positioned to give a desired pressure in the conduit 2, the 45 controller parts are so adjusted that the vapor pressure will force sufficient condensate from the reservoir 10' into the receptacle 16 to weight the latter sufficiently to maintain the valve in normal position against the bias imparted by the counter-balance 5' on the valve arm 5; the nozzle 15 being so adjusted that its mouth 19 is substantially coincident with the normal level of the condensate in the receptacle 16. If further condensate accumulates while the pressure in the conduit 2 is constant, such excess escapes through

the pipe 11 and trap 12 so that the quantity of condensate in the reservoir 10' and receptacle 16 is substantially constant so long as the pressure in the conduit 2 is constant. Should the vapor pressure in the conduit 2 rise, condensate is forced from the reservoir 10' into the receptacle 16, thereby increasing the weight of the latter and pulling the valve stem 4 toward closing position. The air displaced from the receptacle 16 by the additional condensate escapes through the valve port 22, but should the excess pressure in the conduit 2 be so great as to entirely fill the receptacle 16 and the valve body 21, the float valve 23 closes the port 22 and prevents the overflow of liquid. As soon as the pressure in the conduit 2 drops to normal, condensate flows from the receptacle 16, through both ports 19 and 18 of the nozzle 15, back to the reservoir 10', thereby rapidly lightening the vessel 16 until the level of liquid therein is back to the original setting. If the pressure in the conduit 2 falls below normal, the liquid in the receptacle 16 escapes slowly through the port 18 back to the reservoir 10', thereby permitting the counterweight on the lever 5 to slowly lift the valve stem 4 and open the valve to permit the ingress of additional steam. The condensate from the system will quickly make up any loss of condensate resulting from its escape through the discharge pipe 11 as a result of the return of condensate from the vessel 16 to the reservoir 10'.

Instead of making the valve-control receptacle cylindrical it may be made of irregular cross section, such for instance as the spherical or spheroidal receptacle shown in Fig. 4. In the construction illustrated in Fig. 4, the spheroidal receptacle 16a is supplied with condensate from the reservoir 10' through the nozzle 15a having the ports 18a and 19a. The port 19a is normally positioned slightly below the center line of the vessel and there is therefore an equatorial zone in the receptacle in which very slight changes in surface level will effect a substantial change in the weight of the vessel's contents and hence of the force applied to the valve arm 5. Increased sensitiveness of the apparatus to variations of vapor pressure from normal may be thereby secured without abnormally weighting the valve arm 5 during normal operation.

Having described my invention, I claim:

1. A flow controller comprising a valve conduit, a liquid reservoir, means communicating with and supplied with fluid from said conduit, a vessel operatively connected with and controlling the valve of said conduit and a flexible tube connecting said reservoir and vessel, said tube having a section projecting into said vessel and provided with an end port and a side port at different distances from the bottom of said vessel to rapidly fill and more slowly drain said vessel.

2. A flow controller comprising a valved conduit, a vessel operatively connected with and controlling the valve of said conduit, means for supplying liquid to said vessel from said conduit in response to a rise in pressure in said conduit and for draining said vessel in response to a pressure drop in said conduit, said means connecting said conduit and vessel and forming a plurality of ports communicating with said vessel and one of which is of larger area and at a greater distance from the bottom of the vessel than the other port so that the vessel may be filled with liquid above the upper port through both of said ports more rapidly than it can be

drained below the upper port through the lower port alone.

3. A method of controlling the flow of a condensable vapor which comprises condensing a portion of such vapor in a receiver, expelling from said receiver variable portions of the condensate by the pressure on the condensate of uncondensed vapor and controlling the supply of vapor by variations in the weight of the expelled portions of condensate which vary the elevation of the expelled condensate, relatively to the point of expulsion thereof from the receiver, inversely to the weight of condensate expelled so that the greater the weight of the condensate portions expelled the lower the elevation thereof.

4. In a heating system including a high pressure steam supply line and a low pressure radiating circuit with which said line constantly communicates, means for maintaining the pressure of steam in the radiating circuit substantially constant and comprising a condensate collector means constantly communicating with the radiating circuit, means for maintaining in the collector a substantially constant quantity of condensate so long as the pressure in the radiating circuit is substantially constant, a reducing valve mechanism including a valve between the high pressure line and low pressure circuit, a hollow vessel suspended from said mechanism for operating said valve, and a conduit through which condensate flows back and forth between the interior of said vessel and collector means with variations in the pressure in said radiating circuit and thereby varying the weight suspended from said valve mechanism.

5. The combination with a conduit and condensate-receiver-means communicating therewith, of weight-operable valve mechanism controlling flow between said conduit and means, a liquid container supported by said valve mechanism in weight-operating relation thereto, and a tube connecting said container and means and through which tube condensate flows backward and forward between said container and means to vary the weight of the contents of said container and the stress thereby imparted to the valve mechanism with changes in pressure on condensate in said means.

6. A flow controller comprising a conduit including a valve mechanism, valve-operating means operatively connected with said valve mechanism and including a liquid container having a plurality of ports for supplying liquid thereto and draining liquid therefrom, one of said ports being higher than the other so that the container may be filled with liquid above the upper port more rapidly than it can be drained below such port, and condensate receiver means connected with said conduit and communicating through said ports with said container.

7. A flow controller comprising a conduit including valve mechanism, valve-operating means operatively connected with said valve mechanism and including a liquid container having an air-escape port, a float-operable valve in said container for closing said air-escape port when the container is full, and condensate-receiver means communicating with said conduit and container.

8. The combination with a conduit and condensate-receiver means communicating therewith, of weight-operable valve mechanism controlling flow between said conduit and means, a liquid container suspended from said valve

mechanism and imparting stress to the valve mechanism proportional to the weight of the contents of said container, an air-escape port in said container, a float-operable valve controlling said port, said container having therein means forming a plurality of ports for supplying liquid thereto and draining liquid therefrom, one of said ports being below and smaller than

the other so that said container may be filled more rapidly than it can be drained, a flexible tube connecting said means with said ports, and a trapped discharge pipe communicating with said means above the connection of said flexible tube therewith.
